CIGARETTE LIGHTER

Irving Florman, New York, N. Y.

Application September 27, 1937, Serial No. 165,991

6 Claims. (Cl. 67—7)

My invention relates to cigarette lighters and particularly to lighters of the catalytic flameless type.

The primary object of the invention is to provide a lighter of this type which is simple and easy to operate, and which can be conveniently carried in the pocket of the user.

Another object of the invention is to provide a lighter formed of two casing sections which upon separating movement expose the lighting element, with means for sealing off the lighting element from the fuel chamber and also for closing the fuel chamber when the two casing sections are brought together.

A further object of the invention is to provide a lighter of this type most of the parts of which can be produced by die-casting of metal, or molded of plastic material.

Still another object of the invention is to provide a lighter in which the axis of the ignition element is transverse to the direction of movement of the casing parts, while the passage connecting this element to the fuel chamber is parallel to such direction at least in part, with means carried by one of the sections slidable in such parallel part of the passage for sealing it and thus closing off communication between the igniting element and the fuel chamber.

Still another object of the invention is to provide means movable without one of the casing sections to engage and cover the lighting element when the casing sections are closed so as to protect it and exclude air therefrom.

Further objects and advantages of the invention will appear more fully from the following description, particularly when taken in conjunction with the drawings, which form a part thereof:

In the drawings:

Fig. 1 is a side elevation of my lighter in closed position;

Fig. 2 is a similar view of the same in open, operative position;

Fig. 3 is a top plan view of the same;

Fig. 4 is a cross section on the line 4—4 of Fig. 1;

Fig. 5 is a cross section on the line 5—5 of Fig. 2;

Fig. 6 is a cross section on the line 6—6 of Fig. 3;

Fig. 7 is a side elevation of one end of the lighter in partly open position with one of the casing sections removed;

Fig. 8 is a cross section on the line 8—8 of Fig. 7.

As shown, the casing comprises two relatively slidable sections 2 and 4. Mounted by a friction fit within the section 2 and extending beyond the open end thereof is a die-cast or molded plastic element generally indicated at 6. This element comprises a section 8 forming a fuel chamber which is filled with absorbent cotton 10 or other suitable material for holding fuel. The fuel chamber is closed by a top or end wall 12 except for the passages to be described below. This fuel chamber fills substantially the whole of the base casing section 2.

The die-cast member 8 extends out into the cover section 4, having a block or projection 14 of substantially solid metal with certain passages 15 therein, and on which the cover section 4 is slidably guided. The passages in the block include a large bore 16 open at the end nearest the cover and having at its inner end a seat 18 communicating with the fuel chamber. This bore extends in the direction of movement of the casing sections. Also located in the block 14 is an aperture 20 communicating with the passage 16 and extending transversely thereto. Furthermore, near one edge of the lighter there is provided in the block 14 a small aperture 24 within the end wall of chamber 10.

Arranged above the mouth of the passage 20 is a shoulder 26 which forms a seat for a cup 30. Said cup 30 is frictionally held by the walls adjacent the shoulder 26. The bottom of cup 30 is perforated at 36, and supports a catalytic material 34 of a well known type. A screen 32 covers the material 34.

This type of lighter is well known, in which when a cigarette is applied to the catalytic pill or lighting element and suction applied it will draw vapors through the catalyst, which will become sufficiently hot to ignite the cigarette.

Mounted in the cover section 4 is a plate or element 38 which is secured to the end wall of the cover. Rigidly mounted on member 38 and extending into passage 16 is a cylinder 40 having a free end adapted to engage within a ring or ferrule 44 of rubber or other packing material arranged in the bottom of the passage 16. It is evident, as shown in Fig. 5, that when the cover member 4 is pushed into closed position the plunger 40 will engage in the ring 44 and thus will seal the passage between the fuel chamber 6 and the catalytic pill 30. Thus when the lighter is not in use there is no passage for fuel from the fuel chamber to the pill. As soon, however, as the casing sections are pulled apart the pill is exposed through the opening therebetween.

and communication is opened between the pill and the fuel chamber.

At the same time, the plate 38 is extended into a spring member 46 which carries a cushion 66 of rubber opposite the aperture 24, so as to seal the other opening of the fuel chamber when the casing sections are brought together.

There is also provided an extension 48 on the plate 38 of flat spring metal. This plate, when the casing sections are moved together, engages and overlies the upper edges of cup 30 so as to close it off from the atmosphere. Obviously when the casing sections are open plate 48 moves off and uncovers the cup as shown in Fig. 2.

In order to limit the relative movement between the casing sections, I provide grooves 52 in the opposite sides of block 14, these grooves having at their ends ridges or shoulders 54. Secured to the plate 38 are extensions or tongues 20 having at their free ends noses or hooks 58. The noses 58 run in the grooves 52, while the members 56 slide past the ridges 54. When the cover is moved outwardly until the plate 38 reaches the position shown in Fig. 5, the noses 58 engage the ridges 54 and thus prevent further separating movement between the cover and the lighter body.

In order to fill the lighter, the cup 30 is gripped and pulled out of the casing. The device is then filled by pouring fuel into the opening 20, after which the catalytic element is replaced.

While I have described herein one embodiment of my invention, I do not intend to limit myself thereby except within the scope of the appended claims.

What I claim is:

1. A cigarette lighter comprising two sections substantially centrally divided and together forming a casing, a die-cast member mounted in one of said casing sections, said member having a space therein forming a fuel chamber, and having a projection extending from the said casing section, the second casing section being slidably engaged in said projection, said projection having a passage therein extending in the direction of relative movement of said sections and communicating with said fuel chamber and extending to the end of said projection, and a second passage communicating with said first passage and at an angle thereto, a flameless catalytic ignition element mounted in the end of said second passage, a sealing member at the inner end of said first passage, a cylindrical member carried by said second casing section and slidable in said first passage and having an end engageable with said sealing member.

2. A cigarette lighter comprising two sections substantially centrally divided and together forming a casing, a die-cast member mounted in one of said casing sections, said member having a space therein forming a fuel chamber, and having a projection extending from the said casing section, the second casing section being slidably engaged on said projection, said projection having a passage therein extending in the direction of relative movement of said sections and communicating with said fuel chamber and extending to the end of said projection, and a second passage communicating with said first passage and at an angle thereto, a flameless catalytic ignition element mounted in the end of said second passage, a sealing member at the inner end of said first passage, a cylindrical member carried by said second casing section and slidable in said first passage and having an end engage-

able with said sealing member, and a flat plate carried by said second casing section and slidable to a position above and engaging said ignition element.

3. A cigarette lighter comprising two sections substantially centrally divided and together forming a casing, a die-cast member mounted in one of said casing sections, said member having a space therein forming a fuel chamber, and having a projection extending from the said casing section, the second casing section being slidably engaged on said projection, said projection having a passage therein extending in the direction of relative movement of said sections and communicating with said fuel chamber and extending to the end of said projection, and a second passage communicating with said first passage and at an angle thereto, a flameless catalytic ignition element mounted in the end of said second passage, a sealing member at the inner end of said first passage, a cylindrical member carried by said second casing section and slidable in said first passage and having an end engageable with said sealing member, and a flat plate carried by said second casing section and slidable to a position above and engaging said ignition element, said projection further having a passage therein communicating with said fuel chamber and means carried by the second casing section for closing said passage.

4. A cigarette lighter comprising two sections substantially centrally divided and together forming a casing, a die-cast member mounted in one of said casing sections, said member having a space therein forming a fuel chamber, and having a projection extending from the said casing section, the second casing section being slidably engaged on said projection, said projection having a passage therein extending in the direction of relative movement of said sections and communicating with said fuel chamber and extending to the end of said projection, and a second passage communicating with said first passage and at an angle thereto, a flameless catalytic ignition element mounted in the end of said second passage, a sealing member at the inner end of said first passage, a cylindrical member carried by said second casing section and slidable in said first passage and having an end engageable with said sealing member, and a flat plate carried by said second casing section and slidable to a position above and engaging said ignition element, said projection further having a passage therein communicating with said fuel chamber and means carried by the second casing section for closing said passage, said projection having grooves in opposed sides thereof provided at their outer ends with ridges, and flexible resilient members carried by said second section having noses engaging in said grooves whereby to limit relative sliding movement between said sections.

5. A cigarette lighter comprising two sections substantially centrally divided and together forming a casing, one of said casing sections having a space therein forming a fuel chamber, and having a projection extending from the said casing section, the second casing section being slidably engaged on said projection, said projection having a passage therein communicating with said fuel chamber, a flameless catalytic ignition element mounted in communication with said passage, means carried by said second casing section operable upon relative closing movement between the sections to close said passage,

said projection having grooves in opposed sides thereof provided at their outer ends with ridges, and flexible resilient members carried by said second section having noses engaging in said grooves whereby to limit relative sliding movement between said sections.

6. A device as claimed in claim 5 in which the axis of said lighting element is perpendicular to the direction of sliding movement between the sections.

IRVING FLORMAN. 5
